UNITED STATES PATENT OFFICE

2,450,942

MULTIPLE BLADE HACKSAW

Thomas Donnelly, Wilmington, Calif.

Application March 8, 1946, Serial No. 653,097

2 Claims. (Cl. 145—31)

1

This invention relates to hacksaws, and more particularly to a hacksaw employing multiple blades.

A main object of the invention is to provide a novel and improved hacksaw structure wherein a plurality of blades may be simultaneously mounted for obtaining multiple cutting action of the saw.

A further object of the invention is to provide an improved hacksaw structure wherein two blades may be accommodated, one of the blades serving as a guide to insure constant thickness of the portion being cut off by the other blade.

A still further object of the invention is to provide an improved hacksaw structure wherein the blade may be positioned in any one of a plurality of laterally offset positions with respect to the axis of the saw frame whereby operation of the saw in close quarters will be facilitated.

Further objects and advantages of the invention will become apparent from the following description and claims, and from the accompanying drawing, wherein:

Figure 1 is an elevational view of a hacksaw constructed in accordance with the present invention.

Figure 2 is a detail elevational view of a tensioning bolt member employed in the hacksaw structure of Figure 1, showing the end portions of a plurality of hacksaw blades engaged therewith.

Figure 3 is a cross-sectional view taken on line 3—3 of Figure 2.

Figure 4 is a top plan view of the structure of Figure 2.

Referring to the drawing, 11 designates a conventional hacksaw frame having a first section 12 provided with a handle 13, and a second section 14 telescopically engaging the first section 12 for longitudinal adjustment thereon in a well known manner. Rigidly secured to the first section is a leg member 15 carrying a loop element 16 for receiving a first hacksaw retaining bolt, second section 14 being provided with a leg member 17 carrying a loop element 18 aligned with loop element 16 for receiving a hacksaw tensioning bolt. The structure thus far described is conventional and forms no part of the present invention.

A bolt member 19 is formed with a threaded free end portion which is extended through said loop 16 toward said handle. Such threaded portion of the bolt is adapted to receive a tension-resisting nut 19' which engages the handle side of the loop element 16 to prevent withdrawal of

said bolt in the opposite direction. The shank portion of bolt member 19 is formed on each side with a plurality of stepped sections 20, 21 and 22, there being three such sections shown herein but any desired number of sections being contemplated within the spirit of the invention. The inner section 20 is of least thickness, the next section 21 of greater thickness and the last section 22 of greatest thickness. Each section is provided with a pair of laterally projecting hacksaw engaging pins symmetrically located thereon.

Engaged in loop element 18 is a tensioning bolt member 23 whose outer portion is threaded to receive a conventional tensioning wing nut 24 and whose shank portion is similar in all respects to the shank portion of bolt member 19, there being a plurality of stepped sections 25, 26 and 27 of graduated thickness whose side surfaces are respectively aligned with the side surfaces of stepped sections 20, 21 and 22 of bolt member 19. Each of the stepped sections 25, 26 and 27 is provided with a pair of laterally projecting hacksaw engaging pins symmetrically disposed thereon.

A hacksaw blade 28 may be secured in frame 11 by engagement with the pins carried by sections 20 and 25, 21 and 26 or 22 and 27 on either side of the plane of frame 11. This provides a range of six different offset positions of the blade with respect to the plane of the frame, where only one blade is employed, enabling the operator to set the blade in the best position on the frame for a particular job. This is highly advantageous, especially when working in close quarters.

Alternatively, a pair of symmetrically mounted blades may be employed in the frame 11 to provide a double cut where desired, or one of the blades may be employed as a guide for insuring constant thickness of cut where it is desired to remove a slice of constant known thickness from the end of a bar or other object.

Finally, a plurality of pairs of symmetrically mounted blades may be employed in frame 11, as shown by way of illustration in Figures 2, 3 and 4, to obtain a multiple saw cut, such as multiple grooves of accurate and constant spacing in a work piece.

Although described above in connection with a hand tool, the hacksaw blade engaging bolt members 19 and 23 may be similarly employed in a power saw frame.

While a specific embodiment of a hacksaw structure has been disclosed in the foregoing description, it will be understood that various modifications within the spirit of the invention may occur to those skilled in the art. Therefore it is

intended that no limitations be placed on the invention other than as defined by the scope of the appended claims.

What is claimed is:

1. Blade-holding and tensioning means for a hacksaw, comprising a pair of bolts, means for supporting and tensioning said bolts, each bolt having a shank including outer side faces and a free end, at least one of said faces comprising a plurality of inwardly offset stepped portions toward said free end, and means on each stepped portion for detachably connecting a hacksaw blade thereto.

2. Blade-holding and tensioning means for a hacksaw, comprising a pair of bolts, each bolt having a shank including opposed outer side faces and a free end, both of said side faces comprising a plurality of inwardly offset stepped portions toward said free end, and means on each stepped portion for detachably connecting a hacksaw 20

blade thereto, means mounting said bolts in longitudinally spaced relation with corresponding stepped portions opposed and aligned, means for tensioning said bolts, said means on each pair of aligned stepped portions of said bolts being each adapted to support a blade of different length.

THOMAS DONNELLY.
